UNITED STATES PATENT OFFICE
2,518,823
BOTTLE CARRIER
Doris M. Schneider, Raspeburg, Md.
Application November 13, 1945, Serial No. 628,070
1 Claim. (Cl. 294—87.2)

1
This invention relates to containers and more particularly to a carrier for bottles that can be held and manipulated by the hand.

Most light weight carriers for beverage bottles require considerable material and sustain the bottles by the bottom. The disadvantages of these carriers, are that they are relatively expensive to manufacture and use, and require considerable time and care in the placement of the bottles therein.

It is an object of the invention to provide a new and improved bottle carrier that will avoid one or more of the disadvantages and limitations of the prior art.

Another object of this invention is to provide a new and improved bottle carrier that will permit the bottle carried to be secured by the neck.

An additional object of the present invention is to provide a new and improved bottle carrier, that can be attached to or removed from the bottles expeditiously and will tend to tighten on them in place as they are carried along in it.

Still another object of this invention is to provide a new and improved bottle carrier, that can be constructed in a form economical in the use of material and therefore light and non-cumber-some.

For a better understanding of the invention reference is made to the appended drawings and following description, of a form of the invention used to illustrate its general manner of operation and the principles under which it operates, while the scope of the invention is pointed out in the claim.

Figure 1 is a plan view of a bottle carrier embodying this invention.

Figure 2 is a side elevation of Figure 1.

Figure 3 is a sectional view taken along line 3—3 of Figure 1.

Figure 4 is a bottle carrier in the modified form, and

Figure 5 is a sectional view taken along line 5—5 of Figure 4.

Similar reference characters refer to similar parts throughout the drawings.

Referring to Figure 1, in which the carrier is shown with six bottles in dotted outline, assembled in it, the carrier comprises a single plate 10 of sturdy flat material bent slightly to provide a middle flat portion 11 from which the sides 22 extend downwardly and transversely therefrom as indicated in Figure 2. Three sets of openings 12 are cut transversely in the plate 10 having their ends 13 semi-circularly formed with tangent border lines 14 running towards the

2
middles which are enlarged to a larger diameter 23, sized to permit the cap-ends or heads 15 of the beverage bottles 16, to be inserted therethrough. The restricted spaces between the border lines 14 however will engage the necks 17 of the bottles when they are pushed towards the ends 13 and at such positions the heads 15 cannot pass through because they are larger than the spaces and the ends 13. A horizontal handle 18 is secured to the lugs 19 through links 21. It is placed longitudinally over the normal center of gravity of the carrier filled with bottles. This arrangement of parts of the handle enables it to be close to the upper surface of the plate 10, when not in use.

When the bottles are placed in the carrier, the raising of the carrier causes them to drift to the ends 13 and bend the plate more angularly. The sides of the bottles contact and prevent further bending. The bending however produces a wedging action of the sides 14 of the openings which tightens up on the necks of the bottles. The bent portion of the plate in a slanting direction from the flat middle portion, downwardly, makes the plate more rigid.

In the modified form, shown in Figure 4, six bottles are carried in it, but otherwise the construction is similar to previous form described except that the plate is bent in reverse to Figure 2 and the bottles are inserted peripherally.

While but two general forms of the invention are shown in the drawings and described in the specification it is not desired to limit this application for patent to these particular forms or in any other way otherwise than limited by the scope thereof, as it is appreciated that other forms could be made that would use the same principles and come within the scope of the appended claim.

Having thus described the invention what is claimed is:

A carrier for bottles having heads and restricted neck portions immediately therebeneath, comprising a generally rectangular flexible plate having a central flat portion extending lengthwise thereof, the plate further including opposed normally flat side portions extending downwardly and transversely of said flat portion, and having outwardly convexed free edges in the planes thereof, said plate being provided with elongated openings extending through and transversely of said flat portion, into said side portions and terminating inwardly of the convexed edges thereof, said openings being in parallel relation and being spaced from each other to provide sub-

stantial width of material therebetween for adequate strength to sustain the weights of bottles when supported in said openings, said openings each adapted to support a pair of similar bottles and including opposed parallel edges spaced apart substantially equal to the diameters of said restricted neck portions, the opposed edges merging into opposed arcuate edges centrally of the openings whose diameters are substantially equal to that of the heads of the bottles for admission thereof into the portions of the openings defined by said parallel edges, and the said parallel edges merging into semi-circular edges at the opposite ends of the openings for engaging the neck portions of the bottles in their carrying position, said downwardly extending side portions inducing the bottles when admitted through the central portions of the openings to gravitationally slide towards said end portions and be engaged by said semi-circular edge portions, and a handle fastened to said flat portion and including a horizontal and two vertical links

to give swinging flexibility thereto while in use and collapsible on the plate when not in use, the flexible plate bending under the weights of the bottles supported thereby and tending to induce a frictional grip of said parallel edges of the openings on the necks of said bottles.
